Primary Examiner — Rashida C. Walshon*(74) Attorney, Agent, or Firm* — Jonathan A. Bay(57) **CLAIM**

The ornamental design for a boot with ammunition holder, as shown and described.

DESCRIPTION

FIG. 1 is a perspective view of a boot with ammunition holder showing my new design;

FIG. 2 is a side elevational view thereof;

FIG. 3 is a front elevational view thereof;

FIG. 4 is a rear elevational view thereof;

FIG. 5 is a top plan view thereof; and

FIG. 6 is a bottom plan view thereof;

FIG. 7 is a perspective view comparable to FIG. 1 except of an alternate embodiment of a boot with ammunition holder showing my new design, wherein the ammunition holder extends not on an inclined axis but closer to a horizontal axis;

FIG. 8 is a side elevational view comparable to FIG. 2 except of the FIG. 7 embodiment;

FIG. 9 is a front elevational view of the FIG. 7 embodiment;

FIG. 10 is a rear elevational view of the FIG. 7 embodiment;

FIG. 11 is a top plan view of the FIG. 7 embodiment;

FIG. 12 is a bottom plan view of the FIG. 7 embodiment;

and,

FIG. 13 is an opposite side elevational view thereof.

The broken lines in the drawing represent environmental subject matter that forms no part of the claimed design.
